UNITED STATES PATENT OFFICE.

JAMES H. MYERS, OF TROY, NEW YORK.

SHIRT.

SPECIFICATION forming part of Letters Patent No. 594,140, dated November 23, 1897.

Application filed July 8, 1896. Serial No. 598,367. (No model.)

To all whom it may concern:

Be it known that I, JAMES H. MYERS, a citizen of the United States, residing at Troy, county of Rensselaer, and State of New York, 5 have invented certain new and useful Improvements in Shirts, of which the following is a specification.

The invention relates to such improvements; and it consists of the novel construction and combination of parts hereinafter described and subsequently claimed.

Reference may be had to the accompanying drawing, and the letters of reference marked thereon, which form a part of this specification.

Similar letters refer to similar parts in the drawing.

I have represented in the single figure of the drawing a view in elevation of the inner 20 end of a sleeve and the neighboring body portion of a shirt embodying my invention.

A represents the body portion of the shirt, which may be made of any suitable material and of any desired pattern. The body is provided with the usual arm or sleeve apertures, 25 one of which is shown at B.

C is the sleeve, made in a separate piece from the body portion and secured in the sleeve-aperture B. The inner end of the 30 sleeve is secured to the shirt-body by inserting one or more rows of stitching S through both the sleeve and body portions of the shirt from a point S' at or near the middle of the sleeve on the front side over the top of the 35 sleeve to a similar point on the back thereof. The edge of the sleeve on the under side between the terminals of the stitching S is disconnected from the body portion of the shirt and rests loosely within the sleeve-aperture, 40 as shown. The disconnected edges of the sleeve and body portion are separately finished, as by the hems D and D'.

My improved construction permits the sleeve portion of the shirt to be moved with 45 the arm of the wearer without strain upon or movement of the body portion under the arm.

As shirts are commonly constructed the elevation of the arm of the wearer draws more or less of the body of the shirt out through the armhole of the vest or waistcoat. 50 As there is no downward tension on the shirt-body, the portion so drawn through the arm-hole of the outer garment fails to return therethrough when the arm is again lowered, but remains bunched beneath the arm to the 55 great discomfort of the wearer. By my improved construction I am able to avoid drawing up the body of the shirt when the arm is elevated, the disconnected portion of the sleeve partaking of the arm movements independently of the body portion. By leaving the edges of the sleeve and body portion disconnected on the under side I also provide a ventilating-opening in a part of the garment where ventilation is most needed. By extending the lower end of the sleeve a considerable distance into the sleeve-aperture, as 60 shown, no opening is exposed to view by the arm movements, and the difference in construction between my improved shirt and the 65 ordinary shirt is rendered inconspicuous.

What I claim as new, and desire to secure by Letters Patent, is—

A shirt comprising a body having a sleeve-aperture and a sleeve secured to the body in 75 communication with the aperture by a seam extending around the upper side of the sleeve and terminating at or near the middle thereof at front and back respectively, the sleeve having its lower part loosely inserted in the 80 lower portion of the aperture, and the loose edges of the sleeve and body being separately finished, substantially as described.

In testimony whereof I have hereunto set my hand this 6th day of July, 1896.

JAMES H. MYERS.
